[57] CLAIM

The ornamental design for a basket, as shown and described.

DESCRIPTION

FIG. 1 is a front, top and left-side perspective view of a basket showing my new design;
FIG. 2 is a front elevational view;
FIG. 3 is a rear elevational view;
FIG. 4 is a right side elevational view;
FIG. 5 is a top plan view;
FIG. 6 is a bottom plan view thereof; and,
FIG. 7 is a rear, top and right-side elevational view.
The left side view is the mirror image of the right side view.
